UNITED STATES PATENT OFFICE.

OSCAR C. RIXSON, OF NEW ROCHELLE, NEW YORK.

DOOR-HANGER GUIDE.

1,234,805.

Specification of Letters Patent.

Patented July 31, 1917.

Application filed March 21, 1917. Serial No. 156,260.

To all whom it may concern:

Be it known that I, OSCAR C. RIXSON, a citizen of the United States, residing at New Rochelle, in the county of Westchester 5 and State of New York, have invented certain new and useful Improvements in Door-Hanger Guides, of which the following is a full, clear, and exact description.

This invention relates to mechanism for 10 slidably mounting a door or other closure, which mechanism consists of a fixed track, a movable track from which the door is suspended and anti-friction devices interposed between the two tracks which permits the 15 movable track and door to be easily displaced.

The primary object of the invention is to 20 provide a construction of this character, in which slight irregularities or deviations in the raceways from a straight path will not cause a binding of the anti-friction devices but will permit them to have sufficient free 25 lateral movement to compensate for such irregularities or inaccuracies.

It is also the object of the invention to 30 provide this slight lateral movement of the anti-friction devices without permitting the movable track which carries the door, from having a bodily lateral movement.

Another object of the invention is to provide 35 a hanger for suspending the door from the movable track, which hanger will permit of its adjustment after the parts have been assembled.

With these and other objects in view, the 40 invention consists of the constructions and combinations, which will be hereinafter described, in connection with the accompanying drawings, and particularly pointed out in the appended claims.

In the drawings,

Figure 1 discloses the improved track and hanger constructions;

Fig. 2 is an enlarged transverse section 45 through the tracks and associated parts, showing the preferred embodiment of the invention;

Fig. 3 is a side elevation partially in section, of the construction shown in Fig. 2;

Fig. 4 is a plan of a section of the spacer utilized in connection with the anti-friction devices;

Fig. 5 is a central vertical section through Fig. 4;

Fig. 6 is a detail, partially in section, of 55 the hanger construction;

Fig. 7 is a transverse section of the tracks and associated parts, which is of a slightly different form from that shown in the preferred embodiment illustrated by Fig. 2; 60

Fig. 8 is a side elevation, the intermediate portion being omitted, of the movable track formed according to the preferred form of the invention;

Figs. 9, 10, 11 and 12 are views similar to 65 Fig. 2, showing modified constructions.

Referring first to Figs. 1, 2 and 3, the sliding door is indicated at 1, and the fixed door at 2. Arranged above these doors is a fixed track 3, which is of a length equal to 70 the combined width of both doors. This track is supported by brackets 5 which are secured to the frame or wall above the door, the track 3 being secured to the brackets 5 by bolts 7. The track 3 is shaped in cross 75 section as shown in Fig. 2, and consists of a strip of sheet metal bent to form a flat top portion 10 with depending side pieces 11 and 12, and an angularly disposed strip 13 extending from the side piece 11. The 80 lower end of the angularly disposed strip 13 is curved, as shown, to provide a groove or race 14, upon which the balls 15 are adapted to roll. The curvature of the race 14 corresponds to the curvature of the balls, 85 whereby the balls follow the groove without having any independent lateral movement as they roll along it.

The movable track, which is of a length corresponding to the width of the sliding 90 door 1, is designated 16. This track, similar to the fixed track 3, is formed from a strip of sheet metal and consists of a vertically disposed flat strip 17 and a hook-shaped upper portion 18, which curves over the lower 95 portion 13 of the fixed track 3 and the balls 15, as shown in Fig. 2. The door which is secured to the movable track, as is herein- 100 after described, is therefore positioned with its center of gravity in substantially vertical alinement with the centers of the balls 15. A race for the balls is formed upon the inner surface of the hooked portion 18, which, in the preferred embodiment, is of a different shape at its intermediate portion 105 than at its ends. The intermediate portion of this race, as is shown in cross section in Fig. 2, does not form a groove of the same

curvature as the balls, in which the balls must move in a fixed path, but is flattened, as at 18', to provide a race which will permit a relative lateral movement of the track and balls. At the ends 19 of the track, however (see Figs. 3 and 8), the hooked shaped portion curves around the balls to provide a race 20, which is similar to the race 14, that is, of a curvature corresponding to the curvature of the balls, so that the balls and track can have no relative lateral movement.

The advantage of the above described construction will be clear from the following: In securing the fixed track to the frame above a door, the track is frequently bent slightly so that the ball race or groove 14 does not provide a perfectly straight path for the balls. Sometimes this deviation of the race from a straight path is due to inaccuracies in workmanship. If then the movable track is also provided with a ball race which closely surrounds the balls, similar to the race 14, the balls 15 will bind against the sides of the races when the door is moved. This action will cause the movable track and the door to rise and will also prevent them from sliding freely. On the other hand, with the construction described, since the intermediate portion of the movable track has a flat race 18', the balls may then follow the groove or race 14 in the fixed track, although this race is slightly out of true, and at the same time the balls may have a slight lateral relative movement with respect to the movable track, which will prevent them from binding and permit the door to slide freely. However, by making the races 20 at the ends of the movable track in the form of grooves in which the balls can have no free lateral movement, any bodily lateral movement of the movable track is prevented, which will prevent any rattling of the door. It is evident from Fig. 3, that the curved races 20 are relatively short in length, as for example, of only sufficient length to have two of the balls engaging its surface at the same time. No perceptible binding action of the balls in the grooves or races is then apparent for the reason that the deviations in the groove or race of the fixed track from a perfectly straight path, which are most frequently due to slight bending of the track, will be gradual and not confined to a short section of the track.

To prevent the movable track from lifting off the balls 15, rollers 25 are provided, which rollers are mounted upon brackets 25' secured to both faces of the movable track, the roller being mounted in an opening 60 cut in the track so that it is positioned directly below the anti-friction balls 15.

The balls 15 are retained in spaced relation by a spacer which is constructed as shown in Figs. 4 and 5, and consists of a plurality of separate sections, only two of

which are shown, and designated 26 and 27, which parts are pivotally connected together, as by a link 28. Each of the sections 26 and 27 consists of two strips of material which are secured together by rivets 29, and provided with openings surrounded by up-bent ears or lugs 30, which engage the balls and hold them in place. Openings 31 are also provided in both halves of the spacer, which openings are adapted to receive pads 32, which are of felt or other suitable material. These pads contact with the races of both tracks and are preferably saturated with a lubricating fluid to maintain the tracks clean and lubricated.

In Fig. 7, a construction similar to Fig. 2 is disclosed, with the exception that in this form the guide roller 25 is omitted.

In the modification disclosed in Fig. 9, the movable track 16 has a flat ball race 35 which extends the entire length of the movable track instead of being curved downwardly at the ends, as in the preferred embodiment of the invention. Lateral movement of the movable track is prevented in this type of construction, by rollers 36, only one of which is shown, which roller is mounted upon a vertical axis above the movable track and is adapted to engage the inner faces of the side pieces 11 and 12 of the 95 fixed track.

In the modified construction shown in Fig. 10, a fixed track 38 is provided, which consists of a flat vertical strip adapted to be secured to the frame above the door. Extending laterally from the upper end of this flat strip is a V-shaped ledge 39 providing a similar shaped groove or race upon which the balls 15 roll. A movable track 40, which is utilized with this type of fixed track, is substantially U-shaped in cross section, and has its end portions bent down, as at 41, to provide a flat intermediate race and grooved end races for the balls, the function of the flat and grooved races being similar to that described in connection with the preferred embodiment of the invention. To prevent the movable track from lifting, a cylindrical roller 42 is provided which bears against the apex of the V-shaped flange 39 of the fixed track. A cover plate 44 for the fixed and movable tracks may be used with this type of construction, to prevent dust and dirt from settling upon the fixed or movable track and the anti-friction balls interposed therebetween.

The construction shown in Fig. 12 is similar to the construction shown in Fig. 10, with the exception that instead of a cylindrical roller 42 a V-shaped roller 45 is provided, which roller engages the V-shaped flange of the fixed track and will serve not only to prevent the movable track from lifting but will also prevent its bodily lateral movement. With this type of roller, the 130

race formed upon the movable track may therefore be flat for its entire length instead of being bent over at its ends, to provide grooved races of short length, as in the preferred embodiment of my invention.

The modification disclosed in Fig. 11 has a fixed track 46 provided with a downwardly extending flange 47 at the outer end of its horizontal section, which is grooved 10 to provide a ball race 48. A grooved roller 49, which is carried by the movable track, engages the sides of the flange 47 to prevent lateral movement of the movable track as well as to prevent this track from lifting. In this form, as in the form shown 15 in Fig. 12, the flat race formed upon the upper track may extend the entire length thereof.

The door is suspended from the movable track by means of the hanger construction 20 shown most clearly in Figs. 3, 6 and 7. The hanger piece 50, which is stamped from sheet metal, is provided at each end with a pair of spaced lugs or ears 51, which engage 25 both faces of the movable track to which they are secured by rivets 52. The movable track is slotted, as at 53, intermediate the pair of ears 51 and just below this slotted portion the hanger strip is 30 stamped to provide a substantially circular cup-shaped seat 54.

The cup-shaped seat 54 has one of its sides slotted, as at 55. A hanger bolt 56 has its threaded end screwed into a metallic strip 57 carried by the top of the sliding door 1, and has its head 58 fitting into the cup-shaped part 54 of the hanger strip, the bottom of the cup-shaped part being slotted 35 as at 59, for this purpose. The head 58 is rotatable within the cup-shaped part 54 and has intersecting cylindrical passages or holes 60 formed therein, which holes are adapted to receive a nail or other device for turning the hanger bolt. The hanger bolt 40 56 carries a nut 61, which forces a washer 62 up against the bottom of the hanger strip. This washer is provided with an upturned ear or projection 63, which projection 45 engages one of the sides of the bolt to prevent it from turning (see Fig. 6). The advantage of the hanger construction 50 described is that it permits the height of the door to be adjusted after the hanger bolts have been positioned within the hanger strips, for by unloosening the nut 61 the washer 62 may be dropped and the height of the door adjusted by turning the bolt 56, as described, after which the nut 61 may again be tightened, which will force the 55 flange or projection 63 of the washer against one of the faces of the bolt head and prevent a further rotation of the same.

I claim:

1. In a door hanger, a fixed track and a

movable track having raceways formed 65 therein, anti-friction devices in rolling contact with said raceways, one of said raceways being of a width to prevent lateral movement of said devices and the other of said raceways being of a width to permit 70 lateral movement of said devices, and means for preventing bodily lateral movement of said movable track upon lateral movement of said devices.

2. In a door hanger, a fixed track and a 75 movable track having raceways formed therein, balls in rolling contact with said raceways, one of said raceways consisting of a groove of similar curvature to the balls and the other of said raceways having a 80 flat surface with which said balls contact, and means for preventing bodily lateral movement of said movable track when said balls move laterally on said flattened raceway.

3. In a door hanger, a fixed track and a movable track having raceways formed 85 therein, balls in rolling contact with said raceways, the raceway on said fixed track consisting of a groove of the same curvature 90 as the balls, and the raceway on said movable track having a flattened surface upon which said balls are free to move laterally, and means for preventing lateral movement 95 of the movable track.

4. In a door hanger, a fixed track and a movable track having raceways formed 100 therein, balls in rolling contact with said raceways, the raceway on said fixed track consisting of a groove of the same curvature 105 as the balls, and the raceway on said movable track having a surface upon which said balls are free to move laterally, and means for preventing lateral movement of the movable track.

5. In a door hanger, a fixed track and a movable track having raceways formed 110 therein, balls in rolling contact with said raceways, the raceway in said fixed track consisting of a groove of the same curvature 115 as the balls, and the raceway in said movable track having a flattened intermediate portion and end grooves of the same curvature as the balls.

6. In a door hanger, a fixed track and a movable track having raceways formed therein, anti-friction devices in rolling contact with said raceways, one of said raceways being of a width to prevent lateral movement of said devices and the other of said raceways being of a width to permit lateral movement of said devices, means for preventing bodily lateral movement of said movable track upon lateral movement of said devices, and a flexible spacer for said anti-friction devices.

7. In a door hanger, a fixed track and a movable track having raceways formed

- therein, balls in rolling contact with said raceways, one of said raceways consisting of a groove of similar curvature to the balls and the other of said raceways having a flat surface with which said balls contact, means for preventing bodily lateral movement of said movable track when said balls move laterally on said flattened raceway, and a flexible spacer for said balls. 30
- 5 10. In a door hanger, a fixed track and a movable track having raceways formed therein, balls in rolling contact with said raceways, the raceways on said fixed track consisting of a groove of the same curvature as the balls, and the raceway on said movable track having a flattened surface upon which said balls are free to move laterally, means for preventing lateral movement of the movable track, and a flexible spacer for said balls. 35
- 15 11. A spacer for door hanger constructions comprising a plurality of sections pivotally connected together, said sections having openings therein adapted to receive the anti-friction devices. 40
- 20 12. A spacer for door hanger constructions comprising a plurality of sections having flexible connections therebetween, said sections having openings therein adapted to receive the anti-friction devices. 45
- 25
9. In a door hanger, a fixed track and a movable track having raceways formed therein, balls in rolling contact with said raceways, the raceway on said fixed track consisting of a groove of the same curvature as the balls, and the raceway on said movable track having a surface upon which said balls are free to move laterally, means for 50
